US00D918225S

(12) **United States Design Patent** (10) **Patent No.:** **US D918,225 S**
(45) **Date of Patent:** **** May 4, 2021**

(54) **DISPLAY SCREEN WITH A GRAPHICAL USER INTERFACE**

(71) Applicant: **IGT**, Las Vegas, NV (US)

(72) Inventor: **Ernest W. Moody**, Las Vegas, NV (US)

(73) Assignee: **IGT**, Las Vegas, NV (US)

(**) Term: **15 Years**

(21) Appl. No.: **29/688,941**

(22) Filed: **Apr. 25, 2019**

Related U.S. Application Data

(60) Continuation of application No. 29/648,343, filed on May 21, 2018, now Pat. No. Des. 851,103, which is a continuation of application No. 29/584,004, filed on Nov. 10, 2016, now Pat. No. Des. 820,856, which is a continuation of application No. 14/965,408, filed on Dec. 10, 2015, now Pat. No. 9,495,832, which is a continuation of application No. 14/811,283, filed on Jul. 28, 2015, now Pat. No. 9,235,963, which is a continuation of application No. 14/622,391, filed on Feb. 13, 2015, now Pat. No. 9,105,158, which is a continuation of application No. 14/133,085, filed on Dec. 18, 2013, now Pat. No. 9,111,422, which is a continuation of application No. 13/565,005, filed on Aug. 2, 2012, now Pat. No. 8,622,392, which is a continuation of application No. 12/202,815, filed on Sep. 2, 2008, now Pat. No. 8,235,781, which is a division of application No. 11/158,787, filed on Jun. 22, 2005, now Pat. No. 7,431,644, which is a continuation of application No. 10/108,845, filed on Mar. 26, 2002, now Pat. No. 6,964,418, which is a continuation of application No. 09/633,479, filed on Aug. 7, 2000, now Pat. No. 6,652,377, which is a continuation-in-part of application No. 09/175,226,

(57) **CLAIM**

The ornamental design for a display screen with a graphical user interface, as shown and described.

DESCRIPTION

The FIGURE is a front view of a display screen with a graphical user interface showing my new design.

The broken lines showing a display screen and elements of the graphical user interface illustrate portions of the article, and form no part of the claimed design.

1 Claim, 1 Drawing Sheet

Related U.S. Application Data

filed on Oct. 20, 1998, now Pat. No. 6,098,985, which is a continuation-in-part of application No. 09/083, 531, filed on May 22, 1998, now Pat. No. 6,007,066.
